[57] CLAIM

The ornamental design for an angle broom shroud, as shown and described.

DESCRIPTION

FIG. 1 is a front perspective view of an angle broom shroud showing my new design, the broken lines showing of a handle and broom bristles being for illustrative purposes only and forming no part of the claimed design;

FIG. 2 is a top plan view thereof;

FIG. 3 is a front elevational view thereof, the rear elevational view being a mirror image;

FIG. 4 is a bottom plan view thereof;

FIG. 5 is a side elevational view as seen from the right of FIG. 3;

FIG. 6 is a left side elevational view thereof.

FIG. 1

FIG. 2

FIG. 3

FIG. 4

FIG. 5

FIG. 6
